APPARATUS FOR FOLDING WRAPPERS

Robert M. Dunning, St. Paul, Minn., assignor to
 Waldorf Paper Products Company, St. Paul,
 Minn., a corporation of Minnesota

Application October 30, 1947, Serial No. 783,093

5 Claims. (Cl. 93—12)

1

My invention relates to an improvement in method and apparatus for folding wrappers, wherein it is desired to provide a simple and effective means of producing a bag within a box.

In the packaging of cheese and similar products, it is usual practice to mold the cheese within a bag of moisture resistant material and to close the bag about the molded cheese to provide an enclosed brick. This operation may take place either while the bag is in the carton or within a form which holds the bag square until the cheese solidifies. It is desirable, however, that the bags be within the outer carton when filled so that the carton may be thoroughly filled and may act as a form for holding the cheese until it solidifies.

It is the object of the present invention to provide an apparatus for folding flat sheets of moisture resistant and preferably heat sealable material into bags and to provide a means of supporting the bags until they may be inserted into the cartons. Thus the cartons are in readiness for the sealing operation at the completion of the operation.

An object of the present invention lies in the provision of a support and a wrapper of the type described which includes an aperture into which the wrapper may be pressed. By forcing the wrapper into this aperture, the wrapper may be bent into U-shaped cross section as a first step of the bag forming operation. The means forcing the wrapper into the recess comprises an expandable mandrel which may be contracted in size after the bag has been formed to simplify the removal of the bags from the mandrel.

An added feature of the present invention lies in the provision of opposed means which engages the upwardly extending ends of the U-shaped wrapper and folds these ends inwardly over the mandrel. These folding plates are so arranged as to form a seam in the bag by pressing the ends of the wrapper together to seal the same. Usually the wrappers are formed of a transparent film coated with a rubber, wax, resin mixture or other film which may be sealed by pressure alone. However, if desired the ends of the bag may be heat sealed in the same operation.

A feature of the present invention lies in the provision of a means for heat sealing the ends of the wrapper together without pressing these ends against the mandrel within the bag. In view of the nature of the wrapper, the wrapper tends to adhere to any surface against which it is pressed with considerable force, and this is particularly true of the inner surface of the wrapper. The bag sealing mechanism is so devised as to squeeze

the ends of the bag together with the inner surfaces of the bag in surface contact at the seam so as to afford a tight closure without adhering the wrapper to the mandrel.

5 An additional feature of the present invention lies in the provision of a means for restricting the folding of the ends of the wrapper to insure contact between the inner surfaces of these ends at the connecting seam. A blade or arm overlies a surface of the mandrel in spaced relation to this surface. The wrapper is forced between this plate and the mandrel, thus holding the extreme edges of the sheet doubled rearwardly as the sheet is folded to form the seam. As a result portions of the inner surface of the wrapper are pressed together, thus forming a more effective seal than could otherwise be provided.

10 An added feature of the present invention lies in the manner of moving the mandrel into position where a carton having one sealed end may be inserted over the bag, while the bag is held in place by the mandrel. Thus by removing the bag and cartons simultaneously from the mandrel, the proper assembly is provided in readiness for receiving the filling material.

15 Another feature of the present invention lies in the manner in which the carton and bag are simultaneously withdrawn from the mandrel. The liner comprises a soft flexible sheet which 20 has a sealed end adjacent the sealed end of the carton. The carton is of course relatively stiffer and encloses the sealed end of the liner. I have found that by withdrawing the carton quickly from the mandrel any relative movement of the 25 liner tends to create a partial vacuum in the sealed end of the carton and maintains the carton and bag in assembled relation after removal from the mandrel.

30 Another feature of the present invention resides in the provision of a means for stripping the wrapper from the mandrel as the mandrel is contracted. In preferred form the mandrel comprises a pair of opposed plates which may be moved toward each other or away from each other. Any 35 excessive pressure against the wrapper pressing the wrapper against the plates has a tendency to adhere the wrapper to the plates. However, by moving the plates together and by providing stripping pins for stripping portions of the wrapper from the plates, any tendency for the wrapper to adhere thereto is overcome.

35 These and other objects and novel features of my invention will be more clearly and fully set forth in the following specification and claims.

2

In the drawings forming a part of my specification:

Figure 1 is a perspective view of my apparatus showing the construction thereof.

Figure 2 is a vertical section through the apparatus showing the arrangement of the parts thereof.

Figure 3 is a sectional view through a portion of the apparatus, the position of the section being indicated by the line 3-3 of Figure 2.

Figure 4 is a side elevational view of my apparatus, partly in section showing the arrangement of the parts thereof.

Figure 5 is a side elevational view of the mandrel about which the wrapper is folded.

Figure 6 is a sectional view through the mandrel illustrated in Figure 5.

Figure 7 is a perspective view of a portion of the mandrel shown in Figures 5 and 6.

Figure 8 is a perspective view of a detail portion of the operating mechanism.

Figure 9 is a perspective view of the wrapper before the start of the folding operation.

Figure 10 is a perspective view of the wrapper in partially folded form.

Figure 11 is a perspective view of the wrapper after the same has been longitudinally sealed.

Figure 12 is a perspective view showing the mandrel supporting the wrapper in readiness for the end folding operation.

Figure 13 is a perspective view of the wrapper after the end has been folded thereupon.

Figure 14 is a perspective view of a carton for containing the folded wrapper, the carton being shown with one end sealed and the other end opened to receive the wrapper.

The apparatus A is shown as mounted upon a framework generally illustrated by the numeral 10. The framework 10 includes four spaced legs 11 formed of angle iron and held in spaced relation by a suitable shelf 12. At the upper end of the frame the legs 11 are held in spaced relation by a rectangular angle iron frame 13. A rectangular wooden frame 14 is mounted upon the frame 13 for support thereby.

The folding apparatus includes two spaced wall forming members 15 and 16 and a similar pair of outer wall forming members 17 and 19. The wall forming members 15, 16, 17 and 19 are held in properly spaced relation by four strips 20, 21, 22 and 23 which are connected to the undersurface of the various wall forming members to hold the same erect.

The upper ends of the wall forming members are connected by spaced strips which are connected to the upper edges of the wall forming members to hold them in spaced relationship. The wall forming members 17 and 15 are connected by two spaced strips or plates 24, and 25, and by a pair of outer plates 26 and 27. The wall forming members 16 and 19 are similarly connected with a pair of spaced plates 29 and 30 and a pair of outer plates 31 and 32. This leaves the upper end of the space between the wall forming members 15 and 16 open throughout the length of these members. A brace strip 33 is connected to the upper extremities of the wall forming members 17 and 19 to hold these parts in spaced relation and to form a suitable guide which will be later described in detail.

A pair of opposed pressing plates 34 and 35 are slidably mounted on the upper surface of the strips just described in such a manner as to move forwardly and rearwardly toward or away from each other. As indicated in Figure 3 of the

drawings, the plate 34 is guided in its movement by downwardly projecting lugs 36 and 37 which extend in the slots 38 and 39 formed between various of the strips described. The slot 38 is formed between the strips 24 and 26 and the slot 39 is formed between the strips 25 and 27. Removable cross members 40 and 41 are connected by bolts 42 or other suitable means to the lugs 36 and 37 and underlie the various strips to hold the plate 34 locked thereto. At the same time it will be noted that the plate 34 is slideable for a substantial distance forwardly and rearwardly.

The plate 35 is similarly guided and supported. The plate 35 is provided with a pair of spaced lugs 43 and 44 which extend in slots 45 and 46 between various of the strips. The slot 45 is provided by properly spacing the strips 29 and 31, while the slot 46 is provided by properly spacing the plates 30 and 32. Cross members 47 and 49 are secured to the undersurface of the lugs 43 and 44 to underlie the adjacent strips so as to lock the plate 35 upon these strips. The cross members 47 and 49 are removably held in place by bolts 50 or other suitable means.

A yoke is secured to the undersurface of each plate to extend through a slot between certain of the plate supporting strips. The yoke 51 is mounted on the undersurface of the plate 34 to extend through the slot 52 between the strips 24 and 25. The yoke 53 extends through the slot 54 between the strips 29 and 30. Each of these yokes is designed to embrace a cam roller 55 mounted at the upper extremity of a lever arm 56. The manner in which the cam roller 55 is mounted is best illustrated in Figure 8 of the drawings, which shows the roller mounted upon a pivot 57 which is supported by spaced plates 59 projecting beyond the end of the lever arms 56.

A pair of spaced bars 60 are secured to the undersurface of the strips 21 and 22 adjacent the slot 61 therebetween. Pivots 62 extend through the bars 60 to pivotally support the lever arms 56 intermediate their ends. The lower end of each lever 56 is pivotally connected at 63 to a link 64. The links 64 are pivotally connected at 65 to a vertically reciprocable plunger arm 66. By moving the arm 66 downwardly the links 64 act in the manner of toggle levers to spread apart the lower ends of the levers 56 and to allow the cam rollers 55 to act within their yokes to slide the plates 34 and 35 toward each other.

As will be noted in Figure 2 of the drawings the plate 35 is provided with a strip 67 secured thereto along the edge thereof to project beyond the edge of the plate. The plate 34 is provided with two staggered strips 69 and 70 secured thereto in such a manner as to provide a groove between the upper surface of the plate 34 and the strip 70 into which the projecting edge of the strip 67 may extend. This arrangement tends to kink the paper and to insure a tight seam when the edges of the liner are pressed together as will be later described.

A pair of opposed guides 71 and 72 are mounted upon the strips 24 and 25 and the opposed strips 29 and 30 for adjustment toward and away from each other. A third guide 73 is mounted upon the strip 33 for movement at right angles to the movement of the guides 71 and 72 so that the liner sheet may be properly positioned on the table like structure to extend over the central pocket 74 formed therein between the spaced wall forming members 15 and 16.

A pair of forwardly and downwardly inclined arms 75 and 76 are secured to the wall forming

members 15 and 16. These arms are apertured to form a support for a short shaft 77. The position of this shaft may be regulated by means of set screws 78 engaging the ends of the shaft so that the same may be moved axially. A pair of parallel studs 80 project radially from the shaft 77. These studs slidably support an expandable and contractable mandrel illustrated in general by the numeral 82. A pair of short arms 83 and 84 extend radially from the shaft 77. Set screws 85 and 86 respectively extend through the arms 83 and 84 to engage against portions of the mechanism to limit rotative movement of the shaft 77. The mandrel 82 is constructed as best illustrated in Figures 5 and 6 of the drawings. This device includes a pair of substantially rectangular plates 87 and 89 which are slidably connected for movement toward and away from each other. A bar 90 extends between the plates 87 and 89 and supports a pair of blocks 91 near one end thereof and a pair of blocks 92 near the other end thereof. A stud 93 is anchored in the plate 87, extends through aligned apertures in the blocks 91 and the bar 90, and extends into an aperture 94 in the plate 89. A similar stud 95 is also anchored in the plate 87 and extends through the blocks 92 and the bar 90, and extends into an aperture 96 in the plate 89.

Similar parallel studs 97 and 99 are anchored in the plate 89 and extend through apertures in the blocks 91 and 92 and through the bar 90. These studs extend into apertures 100 and 101, respectively in the plate 87. Thus it may be seen that the plates 87 and 89 may move toward each other a limited extent.

A pair of slideable bars 102 and 103 are mounted on opposite sides of the bar 90. These bars 102 and 103 are connected by plates 104 and 105. These plates hold the bars 102 and 103 from movement relative to each other and form an enclosure so that the two bars thus connected may slide longitudinally of the intermediate bar 90.

A pair of links 106 and 107 are pivotally connected on opposite sides of the bars 102 by means of aligned pivots 109. The links 106 are pivotally connected at 110 to brackets 111 mounted upon the inner surface of the plate 87. The links 107 are similarly connected along aligned pivots 112 to brackets 113 mounted on the inner surface of the plate 89. The links 106 and 107 act as toggle levers to move the plates 87 and 89 toward or away from each other upon slideable movement of the connected bars 102 and 103.

A pair of links 114 and a pair of links 115 are pivotally connected at 116 along aligned pivots to the bars 102 and 103. The links 114 are pivotally connected at 117 to brackets 119 mounted upon the inner surface of the plate 87. The links 115 are likewise connected along aligned pivots 120 to brackets 121 mounted upon the inner surface of the plate 89. Thus the links 114 and 115 may act as toggle levers to guide the plates 87 and 89 toward or away from each other upon slideable movement of the bars 102 and 103.

The links 114 are provided with angularly extending flanges 122 and support an end closure plate 123. The links 115 are provided with flanges 124 which support an end closure plate 125. The end closure plates 123 and 125 are arranged in dove-tail relation so as to allow the two plates to close the major portion of the end of the mandrel when the plates are in expanded position. Springs 126 are provided between the plates to urge the plates together.

Suitable means 127 are provided on the bar 90 engageable with the plates 104 to limit longitudinal sliding of the bars 102 and 103 in one direction. Suitable means 127 are provided on the bar 90 engageable with the plates 104 to limit longitudinal sliding of the bars 102 and 103 in one direction. Suitable means 129 on the bar 90 limits the movement of these connected bars in the other direction. In extreme expanded position the pairs of links 106, 107 and 114, 115 move slightly beyond aligned position so that the springs 126 tend to hold the plates in this expanded position. When moving beyond center in the opposite direction, these links may pivot into angular relation so as to substantially reduce the distance between the plates 87 and 89.

A lever 130 is provided with side plates 131 which extend on opposite sides of the angularly turned end 132 of the bar 90. A pivot 133 extends through the plates 131 and through the bar end 132 to pivotally connect the lever 130 to the bar end. Links 134 are pivotally connected at 133 to the lever 130 and at 136 to the bar 102. By pivoting the lever 130 in a clockwise direction, the bars 102 and 103 may be urged to the right to expand the mandrel. When the lever 130 is moved in a counter-clockwise direction the bars 102 and 103 are moved to the left as viewed in Figure 6, tending to contract the mandrel.

An arm 137 is secured to an end of the plate 87 and is bent at right angles at 139 to form an arm 140 substantially parallel to the plate 87. A handle 141 is mounted upon the arm 140 by means of which the movement of the mandrel 82 as a whole may be accomplished. As also illustrated in Figures 1 and 5 a pair of elongated strips 142 and 143 are provided with offset ends 144 secured in surface contact with the plate 87. These strips 142 and 143 act as a guide for the liner during the folding operation in a manner that will be later described. The strips are spaced from the plate 87 a distance sufficient to allow the pressing plates 34 and 35 to extend therebetween.

In order to actuate the plunger 66 any suitable mechanism may be employed. As illustrated in Figure 1 of the drawings, the plunger 66 is guided by a bearing 145 and is pivotally connected at its lower end at 146 to a foot pedal lever 147. The foot pedal 147 is pivotally connected at 149 to a link 150 which is pivotally attached in a manner not illustrated to the undersurface of the shelf 12. A foot pedal plate 150 is attached to the forward end of the lever 147 and a spring 151 connects this lever with the shelf 12 so as to normally urge the pedal plate 150 upwardly. However, when a downward pressure is exerted upon the plate 150 the plunger 66 will be lowered to urge the pressing plates 34 and 35 together.

The operation of my apparatus and the method of folding the wrapper is believed best illustrated diagrammatically in Figures 9 through 14 of the drawings. The lining sheet is indicated in general by the letter B. This sheet is generally rectangular in form and may be printed if desired to provide the necessary display. The liner B is formed of coated paper or in a cellulosic film which may preferably be pressure sealed. Such liner sheets often have a coating of relatively soft material usually containing wax on the inner surface thereof and the base seal is produced by pressing together two portions of this inner surface. One of the difficulties involved lies in the danger of adher-

ing the liner sheet to a mandrel or block about which the sheet is wrapped in the formation thereof. The liner sheet B is first placed upon the apparatus and is held in proper relation thereupon by the guides 71, 72, and 73. This operation takes place while the mandrel 82 is in the upright position illustrated generally in Figure 1 of the drawings.

The next operation consists in pulling the mandrel 82 to the outer end of the slides 88 which support the mandrel, pivoting the mandrel and guides about the axis of the shaft 77 until the mandrel is directly above the liner sheet B. The mandrel is then lowered, pressing the sheet into the pocket 74 and forming the sheet into U-shaped form as best illustrated in Figure 10 of the drawings, the base 152 of the U being beneath the mandrel and between the mandrel and the bottom of the pocket and the sides 153 and 154 of the sheet extending between the mandrel and the wall forming members 15 and 16.

The next step of the operation lies in moving the pressing plates 34 and 35 into contacting relation. This is accomplished by pressing downwardly on the foot pedal plate 150 moving the plunger 66 downwardly and expanding the toggle levers 64. This act pivots the levers 56 outwardly at their lower ends and inwardly at the upper ends, these upper ends acting to urge the plates 34 and 35 together.

As a result the upwardly projecting portions of the liner are pressed between the top of the mandrel and the strips 142 and 143 overlying the mandrel, the paper being doubled rearwardly and rolled over the various edges of the pressing plates as the pressing plates move together. As a result the inner surfaces of the liner may be pressed together by the edges of the pressing plates, these edges being staggered to provide a clamped edge effect as illustrated in Figure 11 of the drawings. As will be seen in this figure the seam 155 which is formed by the pressing plates is adhered together along a plurality of spaced lines of pressure, forming a tight tubular structure.

When the seam 155 has been produced, pressure upon the foot pedal plate 150 is released, allowing the spring 151 to return these plates to retracted position. The mandrel 82 and the slide guides 88 therefor are next pivoted into vertical position as illustrated in Figure 1 of the drawings. During the entire operation, up to the present point, the mandrel 82 is expanded as illustrated in Figure 5 of the drawings so that the tubular bag structure formed is the full size of the mandrel when expanded.

When the mandrel 82 is erected the upper end of the liner projects beyond the upper end of the mandrel as illustrated in Figure 12 of the drawings. This projecting end is provided to permit one end of the tubular liner to be sealed.

This sealing operation could take place during movement of the mandrel from horizontal to vertical position by suitable folding means. However, in the apparatus shown, the upper end of the liner is manually sealed. This is accomplished by folding two opposite side walls of the liner downwardly over the top end of the mandrel which produces a pair of triangular upwardly projecting ears on the remaining two sides of the liner. These triangular ears are next folded to overlie the first folded walls and the bag is closed. Inward sealing pressure may be applied to the top of the bag if desired, this pressure being relatively slight to prevent ad-

herence of the bag to the mandrel end. In actual practice, the first two opposed sides of the bag are folded down onto the mandrel and into overlapping relation, and slight pressure of the fingernail is run across the mandrel along the seam to adhere the layers together. The upwardly projecting ears of the liner are then grasped and the liner is pulled upwardly slightly to disengage the top of the bag from the mandrel. The triangular ears are next folded downwardly into the form illustrated in Figure 13.

An alternative method of folding the end of the carton and one which is preferable in a mechanical operation consists of folding two opposed walls of the cartons so that the marginal edges thereof engage in surface contact while extending upwardly from the mandrel end. As a result the inner surfaces of the sheet are adhered together. The upstanding seam is then folded downwardly and the remaining walls are folded to overlie the first folded walls. While this method forms a tighter end seal it is more difficult to accomplish manually and the first mentioned fold has been employed with success.

The carton C may be any form of tubular carton having rectangular arranged side walls and end closure flaps at both ends of the carton. One end 156 of the carton is preferably sealed before the bag is inserted therein. The carton C with the end 156 closed is then inserted over the mandrel bearing the bag B. Thus the folded bag is positioned within the carton in proper position for the filling operation.

The mandrel 82 is next contracted by pivoting the lever 130 relative to the lever 132. During the contracting operation the plates 87 and 89 move toward each other so as to move inwardly from the walls of the bag. Simultaneously the various guiding pins 63, 95, 97 and 99 project through the plates and tend to strip the bag from the mandrel at any point of adherence thereto. It will be noted that the pins 97 and 99 project through the plate 87 near the center thereof at the point above which the seam 155 was formed. Thus if the ends of the plate have tended to adhere the liner to the mandrel along the center thereof, the pins strip the bag therefrom.

After the mandrel has been contracted the bag and carton are removed therefrom. This is preferably accomplished by a swift upward movement of the carton. If the carton is moved upwardly with sufficient speed, a partial vacuum is created in the top of the carton between the closed end of the carton and the closed end of the bag. As a result the bag is drawn upwardly by the movement of the carton. Obviously if the carton is moved up slowly the air will enter the space between the closed end of the bag and the closed end of the carton and there will be no means of holding the two members assembled. While other means may be employed the foregoing method has proven most successful.

After removal from the mandrel the bag in the carton may be filled and the remaining bag end and carton end may be closed in the conventional manner. The mandrel may next be expanded. A new liner sheet may be inserted upon the apparatus and the same procedure again started.

In accordance with the patent statutes, I have described the principles of construction and operation of my method and apparatus for folding wrappers, and while I have endeavored to set forth the best embodiment thereof, I desire

to have it understood that obvious changes may be made within the scope of the following claims without departing from the spirit of my invention.

I claim:

1. An apparatus for forming a bag including a form having a pocket therein, a mandrel, means pivotally supporting said mandrel for movement from an upright position to one side of said pocket to a position directly above said pocket, means slidably supporting said mandrel for movement from a position above said pocket into said pocket, means for supporting a sheet above said pocket to be bent into U-shaped form by slidable movement of said mandrel, and slidable means for crimping said sheet together above said mandrel.

2. The structure described in claim 1 and including means for expanding and contracting the mandrel.

3. An apparatus for forming a bag including a form having a pocket therein, a mandrel movable into said pocket, said mandrel being operable to press a sheet into the pocket, a pair of opposed members mounted on said form adjacent to said pocket to engage the sheet along lines spaced from the ends thereof and to wrap the ends of the sheet over said mandrel, means engaging the sheet for retarding the ends of the sheet to bring the inner surfaces of the sheet ends into contact, and means pivotally supporting said mandrel for movement from upright position to a position above said pocket, and slidably supporting said mandrel for movement from the position above said pocket to a position in said pocket.

4. An apparatus for forming a bag including a form having a pocket therein, a mandrel movable into said pocket, said mandrel being operable to press a sheet into said pocket, a pair of opposed folding members mounted on said form adjacent to said pocket and movable over the pocket and the mandrel to fold the ends of the

sheet over the mandrel, and means spaced above the folding members for engaging the sheet between the points of engagement of said folding members and the ends of the sheet for holding the ends of the sheet overlying the folding members, said means retarding the movement of the ends of the sheet and causing the inner surfaces of the sheet to come into contact between said folding members, said means comprising a pair of members each having one end secured to said mandrel.

5. An apparatus for forming a bag including a form having a pocket therein, a mandrel movable into said pocket and being operable to press a sheet into the pocket, means on said form engageable with the sheet ends to wrap the sheet ends over the mandrel, and means pivotally supporting said mandrel for movement from upright position to a position above said pocket, and slidably supporting said mandrel for movement from the position above said pocket to a position in said pocket.

ROBERT M. DUNNING.
